UNITED STATES PATENT OFFICE

JOHN H. DAVIS, OF STOCKTON, CALIFORNIA

CONTROL STRUCTURE FOR PLOWS

Application filed June 10, 1929. Serial No. 369,578.

63 This invention relates to gang plows and particularly to a heavy duty plow of the type shown in my previous Patent No. 1,358,929, dated November 16, 1920, over which the present construction is an improvement.

65 The present invention deals principally with the draw bar arrangement and with the mounting of the wheels which support the plow frame. My principal object is to provide a draw bar construction so connected to the frame that a downward pull will be exerted on the same adjacent its rear end, tending to maintain the plows properly engaged with the ground and also so arranged that a lateral tilting of the end supporting 70 wheels to hold the plow in the line of draft is not necessary.

A further object is to provide a wheel supporting the frame on the side thereof opposite the plows, having adjustment means 75 adapted to be readily manipulated to vertically adjust said wheel relative to the frame, so that the latter may be tilted laterally and the plows forced deeper into the ground when operating conditions make this temporarily 80 advisable.

The wheel also has supporting connections with the frame arranged to enable the angle of setting of the wheel relative to the plane of movement of the plow to be altered, there- 85 by relieving or lessening the lateral strain or load on the plows when necessary under cer- 90 tain conditions.

A further object of the invention is to produce a simple and inexpensive device and yet 95 one which will be exceedingly effective for the purpose for which it is designed.

These objects I accomplish by means of such structure and relative arrangement of 100 parts as will fully appear by a perusal of the following specification and claims.

In the drawings similar characters of reference indicate corresponding parts in the several views:

Fig. 1 is a perspective view of one side of 105 the plow.

Fig. 2 is a perspective view of the plow taken from the forward end.

Fig. 3 is a fragmentary top plan showing 110 the specific mounting of the adjustable side wheel.

Referring now more particularly to the characters of reference on the drawings, the frame of the plow comprises a main beam 1, a side beam 2 connected to the beam 1 at its rear end and diverging thence forwardly; and braced cross members 3 connecting said beams at intervals. The rear end of the frame is supported by a single wheel 4 which is vertically adjustable by means of a lever controlled structure 5 as shown in the above mentioned patent. At the forward end of the main beam outwardly of the same is another wheel 6 which is supported from a vertical spindle 7 which is turnable in a sleeve 8 supported from the beam 1. This spindle is vertically adjustable without interfering with its turning by a lever controlled structure 9 also the same as in said previous patent. A plurality of plowing elements 10 is supported by the main beam 1 outwardly of the same and arranged in a row extending lengthwise 15 of the frame.

Journalized in transversely spaced bearings 11 mounted on the frame in a particular manner as later described is a substantial rigid shaft 12 on the end of which opposite the plowing elements is a downwardly and forwardly depending arm 13. On the lower end of this arm, a wheel 14 is mounted which extends substantially parallel to the beam 2 and is disposed about half way between the 20 wheels 4 and 6. A lever 15 projects upwardly alongside the beam 2 and rearwardly of the wheel 14 and is connected at its lower end to a link 16 which is pivoted on said beam. Intermediate its ends this lever is adjustably 25 connected to another link 17 which at its lower end is connected to the lower end of the arm 13. A pawl and ratchet mechanism 30 of common character associated with the lever enables the same to be held at any position.

By means of this arrangement it will be seen that the wheel may be easily raised or lowered relative to the frame at will, resulting of course in raising or lowering the corresponding side of the frame and laterally tilting the frame as a whole. This tends to cause all the plows to be also tilted so that they depend to different extents relative to the wheels 4 and 6 without adjusting the 35 40 45 50 55 60 65 70 75 80 85 90 95 100 105 110

latter and is a valuable feature under those conditions when a temporary altering of the depth of the plow elements is necessary or advisable. The three point suspension of the frame not only simplifies the construction but enables the one side wheel opposite to the plows to be relied on for temporary plow depth adjustment purposes, without having to individually adjust the wheels 4 or 6, the adjustment of the latter being used only when initially setting the plows to a certain constant depth.

The bearing boxes 11 are supported at the ends of a plate 19 which extends across and is secured to the beams 1 and 2 toward the rear end thereof, said boxes being secured by bolts 20 passed through slots 21 in the plate 19 which extend longitudinally of the plow. This arrangement of the boxes and consequently of the shaft causes the latter to brace the frame and to exert a downward pressure on the frame for the full transverse area thereof where most needed; and also enables the said shaft to exert an even tilting action on the frame when the wheel is being adjusted vertically, without tending to then twist the frame. The box nearest the arm 13 has longitudinal adjusting screws 22 mounted in connection therewith at the opposite ends thereof and passing through lugs 23 projecting upwardly from the plate 19.

Therefore if the bolts are loosened and the screws adjusted one way or the other, the angle of the shaft 12 relative to the frame and consequently the angle of setting of the wheel relative to the longitudinal plane of the structure may be altered at will. The link 17, however, is connected to the arm 13 with sufficient loose play or flexibility (as is customary in agricultural implements) so that such shifting of position of the shaft and arm will not interfere with the vertical adjustment mechanism.

Disposed between the beams 1 and 2 just ahead of the plate 19 and substantially in transverse alignment with the second plowing element from the rear is a draw head 24 which is secured to one of the cross bars 3, which at the draw head is bent rearwardly to extend to the beam 1 parallel to the beam 2. This draw head is secured to this extended portion of the brace bar and also to an angled bar 25 engaging the opposite side of the draw head and connected to the beam 1 as shown in Fig. 3. This makes a rigid connection so that the strain of the draw head will be distributed over a considerable portion of the area of the frame adjacent its rear end. A draw bar 26 is swivelly connected to the draw head and extends thence forwardly and downwardly to pass immediately under a cross bar 27 extending between the forward ends of the frame beams and disposed a considerably distance below the same. A yoke 28 is adjustably secured to and under the bar

27 and engages the draw bar to prevent the same from dropping; this yoke being adjustable along the bar so as to allow the angle of set of the draw bar relative to the beams 1 and 2 to be altered at will to suit different conditions.

This mounting of the draw bar with its rear frame connected end being relatively high causes the pull on the draw bar to exert a constant downward pressure on the plow frame so as to prevent the plows from the usual tendency to jump out of the ground in hard dirt. Ahead of the bar 27 the draw bar is pivotally connected to an extension 26a, which extension is adjustably connected to a transverse bar 29 projecting laterally from and connected to the swivel spindle 7 of the wheel 6. Ordinarily, therefore, the draw bar and wheel will be maintained rigid, but the angle of the draw bar may be easily altered as above stated, while the angle of setting of the wheel 6 relative to the line of draft may be likewise easily and independently altered by shifting the point of connection of the bar 29 with the draw bar. Since the draw bar member to which the bar 29 is connected is swivelly mounted relative to the plow frame, it will be evident of course that as said draw bar member is pulled laterally when steering the plow, the wheel 6 will also be turned so as to facilitate the steering operations.

The draw bar normally extends in bisecting relation to the angle between the beams 1 and 2, and in direct line with the tractor holding the same. Uneven strains on the frames 1 and 2 are therefore avoided and it is not necessary to set the wheels 4 and 6 at the angle to the line of movement as is usually necessary to offset the sidewise drag of the draw bar. These wheels therefore turn freely and easily in their bearings and properly follow their path of movement, all side thrusts of the plows being taken by the single wheel 14 which is mounted in a manner to withstand the thrusts, which may be relieved or offset by altering the angle of setting of this wheel as previously stated.

All the wheels are equipped as usual with flanges 30 to prevent side slipping. These flanges in the usual construction are rigid with the wheels but in my improved structure said flanges are formed separately from the wheels and are provided with radial inwardly projecting lugs 31 which are bolted to the wheel webs as shown, so that the flanges may be removed when desired to enable the plow to travel over roads without scoring the surface of the same. The lateral tilting of the wheel supporting arm enables the wheel to be adjusted so that it may be maintained at a suitable operating angle to the ground regardless of the slope of the latter, as on a side hill, and regardless of whether the plow is operating in one direction or another along a hill. This feature makes

my plow very suitable for side hill work, avoiding the tendency to slip down hill which is so evident with ordinary plows. By reason of the point of main connection of the drawbar with the frame being adjacent the rear end of the latter, the drawbar toward its forward end may be connected to the cross-bar 27 on the side thereof adjacent the longitudinal plane of the wheel 14. This enables the tractor to be maintained well to one side of the furrow being made, while at the same time the plow will not pull out of the ground as would be the case with the ordinary plow if the drawbar were connected to the structure in a corresponding lateral point.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

30 1. In plow construction, a main wheel-supported frame, a drawbar pivoted at its rear end on the frame toward its rear end for swinging movement in a transverse horizontal plane, means between the drawbar and frame at the front end of the latter for enabling the drawbar to be held against swinging movement in different angular positions relative to the line of pull, an extension on the drawbar pivoted thereon ahead of said drawbar holding means for horizontal swinging movement, a wheel to one side of said extension mounted on the frame for swivel movement in a horizontal plane, and connecting means between the wheel and the extension to cause them to swing together.

2. In plow construction, a wheel-supported main frame, a drawbar pivoted at its rear end on the frame intermediate the ends thereof and extending thence beyond the front end of the same, a cross-bar secured on the front end of the frame, the drawbar extending under and slidably engaging the cross-bar, and means between the drawbar and cross-bar for holding the former against lateral movement relative to the cross-bar from a plurality of different positions in the length of said cross-bar.

3. A structure as in claim 2, in which said last named means comprises a yoke straddling the drawbar under the cross-bar and engaging the latter, with means for adjustably securing said yoke to the cross-bar.

4. In plow construction, a main frame, said frame including forwardly diverging side beams, a draw-head disposed between the

beams toward their rear ends and extending substantially parallel to one beam, a brace connected to said one beam and extending thence transversely to the draw-head and then rearwardly along one side of the same to the other beam, a bar along the other side of the draw-head and extending to and forwardly along the other beam, and rigid connections between said brace bar and the draw-head.

In testimony whereof I affix my signature.
JOHN H. DAVIS.
